UNITED STATES PATENT OFFICE.

WILLIAM E. WOODARD, OF FOREST HILLS, NEW YORK.

LOCOMOTIVE REAR-END SUPPORT.

Application filed April 27, 1925. Serial No. 26,012.

This application relates to supports at the rear end of locomotives and is in part a continuation of my copending application, Serial No. 576,788, filed July 22, 1922, which 5 has been issued as Patent No. 1,536,036, granted April 28, 1925.

In standard locomotive practice the main frame extends underneath and rearwardly of the firebox, but according to the present 10 invention, the main frame terminates in the region of the forward end of the fire-box, and the rear of the fire box is supported on a truck frame, articulated to the main frame and having capacity for radial motion relative to the fire box. This introduces conditions not present in the old construction with 15 reference to the support of the cab, the stoker mechanism, the grate shakers, and injectors which must be in a fixed relation to 20 the boiler.

It is one of the primary objects of my invention to provide a convenient support for such parts.

In accordance with my invention, there is 25 also a lateral motion furnace bearer device, and it is an object of my invention to transmit load thru the support herein described to such bearer.

How the foregoing, together with such 30 other objects as may hereinafter appear, or are incident to my invention, are realized, is illustrated in preferred form in the accompanying drawings, wherein—

Fig. 1 is a somewhat diagrammatic side 35 elevation of a rear portion of a locomotive equipped with my improvements;

Fig. 2 is an end elevation of the device of Fig. 1, partly in section, such, however, being 40 on an enlarged scale;

Figs. 3 and 4 are respectively a plan view 45 and side elevation of the support of my invention; and

Fig. 5 is a fragmentary side elevation 50 illustrating a modification of the invention.

Referring now to Figs. 1 and 2, the reference numeral 7 indicates the furnace, or firebox of the locomotive, the locomotive being carried on the main frame 8 and on the articulated truck frame 9, before mentioned, 55 such latter frame having one or more axles with wheels.

To the rear of the fire-box 7, is the cab 10 of the locomotive. The other parts, hereinbefore referred to, are indicated as follows:

The injectors by the reference numeral 11; the grate shaking cylinders by the reference

numeral 12; and the stoker by the reference numeral 13. The lateral motion resisting furnace bearer, hereinbefore referred to, is indicated by the reference numeral 14.

The injectors 11, the grate shaker cylinders 12 and the cab with its deck, are supported by the combined support generally indicated by the reference character A. This support, in the main, comprises two 65 side members, preferably castings, which side members are secured to the mud-ring 15 of the fire-box and extend rearwardly thereof. Each side member has a vertical flange 16, by means of which it may be bolted to the 70 lug 17, depending from the mud-ring 15. This flange upstands from the base-plate 18 and unites at the rear with an upstanding plate or flange 19, rising up from the base plate 18. Each side member is secured to 75 the mud-ring by the flange 19 in addition to flange 16. The flange 16 is also braced by the ribs 20 and by the cross member 21, to be referred to hereinafter. Rising from the base plate 18 is another flange or plate 22 80 having a lip 23, sloping downwardly and forwardly. The cross member 21 has two ears 24 which are inclined in the same manner as the lip 23. The lip 23 and the lugs 24 carry the ash pan deflectors indicated at 85 25, such deflectors serving to direct ashes into the ash pan 26, the ash pan proper being carried on the articulated frame 9.

These deflector parts are shown and described in my copending application, Serial 90 No. 10,499 filed February 20, 1925.

The flange 16 is drilled at 27 for the attachment of the deflector plates 28^a which co-operate with the ash pan proper.

Extending rearwardly from the cross 95 member 19 and from the base plate 18 is an I-beam like portion 28, having an end flange 29 for the attachment of the cab plate 30, which in turn supports the cab deck 31 and cab 10. The flange 29 of each side support 100 also carries one of the cylinders 12. The injectors 11 are supported from the plate 30.

Thus it will be seen that in so far as the construction of Figs. 1 to 4 inclusive is concerned, the side members when bolted to the 105 ring and with the plate 30 secured to the flanges 29 thereof, constitute a combined support for the cab and cab deck, the grate shaker cylinders and the injectors, as well as the support for those portions of the ash 110 pan immediately beneath the fire-box and over-lying the ash pan proper 26.

The weight at the rear end of the fire-box is transmitted to the articulated frame thru the lateral motion bearer device 14, hereinbefore referred to, which device is interposed between the base plates 18 and the articulated frame 9, for which purpose the base plates 18 are machined.

Referring now to Fig. 5, the general arrangement is substantially as described. However, the side members A' are of somewhat different configuration and also carry or support the stoker mechanism 13.

It will be seen that the attachment of the side members to the mud-ring is such as to afford great stability and strength.

I claim:

1. In combination in a locomotive, a fire-box having a mud-ring, a cab, ash pan means, and a combined cab and ash pan means support secured to the mud-ring.
2. In combination in a locomotive, a fire-box having a mud-ring, a cab, ash pan means, and a combined cab and ash pan means support secured to the mud ring together with a stoker also carried by said support.
3. In a locomotive having a boiler, fire-box and cab, the combination of a cab support secured to the mud-ring of the box, and an ash pan means for the box supported

from the cab support, said support comprising two members extending along opposite sides of the box and secured to the mud-ring at a plurality of points.

4. In a locomotive having a boiler, fire-box, cab and stoker, a cab and stoker support secured to the box.

5. In a locomotive having an articulated truck under the fire-box, and customary rear end devices, a combined support for the devices adapted to be secured to the mud-ring of the fire-box.

6. In a locomotive having an articulated truck under the fire-box, and customary rear end devices, a combined support for the devices adapted to be secured to the mud-ring of the fire-box, said support also serving as a bearing means for the furnace bearer device.

7. In a locomotive having an articulated truck under the fire-box, and customary rear end auxiliaries, a combined support for the auxiliaries adapted to be secured to the mud-ring of the fire-box, the support having lateral and longitudinal bolting flanges for attachment to the mud-ring corner portions.

In testimony whereof, I have hereunto signed my name.

WILLIAM E. WOODARD.
